[57] CLAIM

The ornamental design for central processing unit for computer, as shown and described.

DESCRIPTION

FIG. 1 is a top, right, front perspective view of a central processing unit for computer showing my new design; FIG. 2 is a top, left, rear perspective view thereof; FIG. 3 is a front elevational view thereof on an enlarged scale;

FIG. 4 is a left side elevational view thereof on an enlarged scale, the right side being a mirror image;

FIG. 5 is a top plan view thereof on an enlarged scale; FIG. 6 is a bottom plan view thereof on an enlarged scale; and

FIG. 7 is a rear elevational view thereof on an enlarged scale.

The connectors are shown in broken lines in FIGS. 2 and 7 for illustrative purposes only and forms no part of the claimed design.
